United States Patent Office

Des. 211,547
Patented June 25, 1968

211,547

MERCHANDISE DISPLAY STAND

Elmer L. Reibold, Park Ridge, William W. Timpe, Prospect Heights, and Spartaco Trivellini, Roselle, Ill., assignors to E. L. Reibold Agency, Inc., Rosemont, Ill., a corporation of Illinois

Filed Apr. 13, 1967, Ser. No. 6,668

Term of patent 14 years

(Cl. D80—9)

Fig. 1

The broken line representation of channel frames for display panels or the like in FIGURES 1 and 2 are for purposes of illustration only.

We claim:

The ornamental design for a merchandise display stand, substantially as shown and described.
